CLAIM

The ornamental design for a diagnostic test device, as shown and described.

DESCRIPTION

FIG. 1 is a top perspective view showing a new design for a diagnostic test device;

FIG. 2 is a top view of the diagnostic test device of FIG. 1; FIG. 3 is a bottom view of the diagnostic test device of FIG. 1;

FIG. 4 is a front view of the diagnostic test device of FIG. 1;

FIG. 5 is a back view of the diagnostic test device of FIG. 1;

FIG. 6 is a right view of the diagnostic test device of FIG. 1; and,

FIG. 7 is a left view of the diagnostic test device of FIG. 1. The broken lines depict portions of the diagnostic test device that form no part of the claimed design.
